THOMAS ROBERT GILLETT PARKER AND WALTER LEE, OF BROADHEATH, ENGLAND,
ASSIGNORS TO LINOTYPE AND MACHINERY LIMITED, OF LONDON, ENGLAND.

DEVICE FOR CLAMPING PRINTING-PLATES TO THE CYLINDERS OF PRINTING-PRESSES.

1,158,269.

Specification of Letters Patent.

Patented Oct. 26, 1915.

Application filed August 18, 1915. Serial No. 46,212.

To all whom it may concern:

Be it known that we, THOMAS ROBERT GILLETT PARKER and WALTER LEE, subjects of the King of the United Kingdom of Great Britain and Ireland, and residing at Linotype and Machinery Works, Broadheath, in the county of Chester, England, have invented new and useful Improvements in Devices for Clamping Printing-Plates to the Cylinders of Printing-Presses, of which the following is a specification.

This invention relates to devices for clamping printing or stereotype plates to the plate cylinders of printing presses, and it has for its object to provide a new or improved mechanism whereby a plurality of plate-clamping dogs can be simultaneously engaged with, or released from, the printing plates on the said cylinders.

The invention will be best understood by reference to the accompanying drawings in which:—

Figure 1 is an end elevation of one half of a plate cylinder with the improved devices applied thereto; Fig. 2 is a longitudinal vertical section taken substantially on the line 2—2 of Fig. 1, as viewed from the right-hand side of that figure, and showing a part of one of the side frames of the press; Fig. 3 is an elevation of the inner end of one of the dogs, and Fig. 4 is a transverse section on the line 4—4 of Fig. 2 of one of the rods.

The clamping dogs 1, 2, 3, which, in the example illustrated, are three in number for each plate 4, are movable each along a groove 5, extending longitudinally of the plate cylinder 6, in the ordinary well-known manner. Each of the dogs 1, 2, 3, as shown best in Fig. 3, is formed with a hole 7 extending therethrough in a direction parallel with the axis of the plate cylinder 6, and through this hole passes a rod 8, 9 or 10 respectively, provided with a series of projections or abutments, 11, 12, corresponding in number to the number of different columnar widths of plates 4, which the device is designed to deal with. Each of the just-named abutments is capable of engaging with the outer side of the respective dog 1, 2 or 3, in order to press that dog into engagement with the edge of the plate 4 to be secured on the plate cylinder 6.

The rods 8, 9, 10, in well-known manner, are journaled in, or engage with, recesses or

open bearings 13 formed in the periphery of a segmental plate 14 which is capable of being moved nearer to or farther from the adjacent end of the cylinder 6. The means illustrated in the accompanying drawings, 60 for effecting the just-mentioned movement of the plate 14, are already known and comprise a screw 15 rigid in the end of the cylinder 6, and having threaded on it a nut 16. This nut is formed with a flange 17 having 65 a curved or partly spherical inner surface seated in a recess in the plate 14 to which latter the nut is permanently retained in swiveled connection by a keeper plate 18 engaging with the outer surface of the 70 flange, and rigidly attached to the plate 14. The inner end of the nut 16 is free to turn within a hole in the plate 14, this hole being sufficiently large to admit of the plate 75 rocking or canting on the nut to any such extent as may be rendered necessary by unevenness or inequalities in the ends of the printing plates 4 clamped by the dogs. By rotating the nut 16 on the screw 15 the plate 14 together with the rods 8, 9, 10, is moved 80 outward or inward according to the direction of such rotation, and through this operation the dogs are all caused simultaneously to release or engage the printing plate.

The before-mentioned abutments 11 are 85 each constituted by the inner end of a collar or enlarged cylindrical part of the respective rod 8, 9 or 10, and they are capable of engaging with the dogs 1, 2, 3, irrespective of angular adjustment of the said rods. 90

Each of the abutments 12 is constituted by the inner ends of a series of wings or ribs 19 extending longitudinally of, and distributed around, the respective rod 8, 9 or 10, and these wings, by angular motion of the rods, 95 are capable of being brought into and out of alinement with grooves 20 in the dogs 1, 2, 3. When the wings 19 are alined with the grooves 20, the dogs 1, 2, 3, can be slid along the rods over the said wings, from 100 the inner to the outer side of the latter, and vice versa, and when, after such movement of the dogs, the wings are turned angularly out of alinement with the grooves 20, the abutments then adjacent to the outer ends 105 of the dogs (whether they be the abutment 11 or 12) can serve for moving the said dogs into engagement with the printing plate.

For enabling the pressman, by a single 110

operation, to turn the rods 8, 9, 10, so as to bring their respective wings 19 all simultaneously into or out of alinement with their respective grooves 20, each of the two rods 8 and 10, has fast on its outer end a crank or lever arm 21, and the rod 9 has fast on its outer end a double crank or two-armed lever 22. All of the parts 21, 22, are preferably situated between the segmental plate 14 and the adjacent end of the plate cylinder 6, and they are provided with crank pins 23, which engage with the forked or slotted ends of two levers 24, 25. The lever 25 is capable of turning freely upon a pivot 26 fast to the segmental plate 14, and the lever 24 is fast to the inner end of a short shaft 27 which extends to the outside of that plate, and has there secured upon it, a hand lever 28 by which it can be rocked to an extent sufficient for moving the wings 19 into and out of the aforesaid alinement. The two terminal positions of the hand lever 28 are determined by two stops 29 fast in the segmental plate 14, and the hand lever can be locked in either of such terminal positions by a bolt 30 screwing into the segmental plate and penetrating either of two holes 31 in the hand lever, according to whether the wings 19 are to be locked out of alinement with the grooves 20 as when the dogs 1, 2, 3, are engaged by the abutment 12, or in alinement with those grooves.

To prevent the dogs 1, 2, 3, from being detached from the rods 8, 9, 10, nuts 32 are threaded and fixed on the inner ends of those rods.

The example illustrated in the accompanying drawings is one which provides for the clamping of two different size printing plates varying to the extent of the width of one column, the dog shown in Fig. 2 being represented as engaging the printing plate having the greater number of columns, and the dotted line 38 in that figure representing what would be the edge to be engaged by that dog, of a printing plate having the lesser number of columns were such plate substituted for the one represented.

The distance between the abutments 11, 12, measured in a direction parallel to the axis of the plate cylinder 6, corresponds or substantially corresponds with the width of a column on the printing plate 4, and in arrangements adapted to clamp printing plates varying to the extent of two or more columns, (as distinguished from the one column in the example illustrated), each of the rods 8, 9, 10, would be provided with two or more sets of the wings or ribs 19, the operative or abutting surfaces of which would be situated in vertical planes at distances apart corresponding or substantially corresponding with the widths of the said columns.

From the foregoing description, it is clear

that when a printing plate 4 of the maximum width is clamped to the cylinder 6 (that is to say the maximum dimension in the direction of the axis about which its curve is generated) the dogs 1, 2, 3, are engaged by the abutments 11, the wings 19 at that time, being locked out of alinement with the grooves 20 by the bolt 30, all as shown in Figs. 1 and 2.

When it is required to clamp a printing plate of one or more columns less width on the cylinder 6, the bolt 30 is unscrewed and withdrawn from the hand lever 28 and the latter is turned leftward to aline the wings 19 with the grooves 20, this movement of the lever 28 being terminated by the respective stop 29 at the instant at which the said alinement is attained. The dogs 1, 2, 3, are then slid along the rods just beyond the particular abutments 12 appropriate to the width of plate to be clamped, and after that the hand lever 28 is turned rightward to move the wings 19 out of alinement with the grooves 20, and (by the bolt 30) locked in the position thus arrived at. The printing plate can then be clamped by the three dogs 1, 2, 3, simultaneously, by turning the nut 16 in the desired direction.

It is to be understood that the before-described arrangement of co-operating cranks and levers is given merely as a convenient example, and that other means may equally well be employed for uniformly turning the rods 8, 9, 10, for instance, each of these rods may have secured thereon a sprocket wheel 100 gearing with a common longitudinally movable endless chain which can be locked in its respective terminal positions by any suitable device.

If desired instead of the bolt 30 being separable from the hand lever 28 as before described, it can be permanently attached to that lever with a capacity for turning and moving axially therein, and be capable of engaging with one or other of two tapped 110 holes in the segmental plate 14.

Having described our invention, we declare that what we claim and desire to secure by Letters Patent is:—

1. In a device for clamping printing plates to a cylinder of a printing press, the combination with a rod movable relatively to the cylinder parallel with the axis thereof, and a dog adapted to be moved by that movement of the rod into and out of engagement with the printing plates and to be moved independently of the rod into and out of engagement with abutments on the rod, of grooves in the dog, an abutment on the rod adapted to operate the dog for clamping plates of one columnar width, ribs on the rod constituting an abutment adapted to operate the dog for clamping plates of another columnar width, and means adapted to bring the grooves and ribs into and out of 130

alinement to permit or prevent the independent movement of the dog.

2. In a device for clamping printing plates to a cylinder of a printing press, the combination with a rod movable relatively to the cylinder parallel with the axis thereof, and a dog adapted to be moved by that movement of the rod into and out of engagement with the printing plates and to be moved independently of the rod into and out of engagement with abutments on the rod, of grooves in the dog, an abutment on the rod adapted to operate the dog for clamping plates of one columnar width, ribs on the rod constituting an abutment adapted to operate the dog for clamping plates of another columnar width, and means adapted to move the rod angularly about its axis to bring the ribs into and out of alinement with the grooves.

3. In a device for clamping printing plates to a cylinder of a printing press, the combination with a rod movable relatively to the cylinder parallel with the axis thereof, and a dog adapted to be moved by that movement of the rod into and out of engagement with the printing plates and to be moved independently of the rod into and out of engagement with abutments on the rod, of grooves in the dog, a plurality of sets of ribs on the rod constituting abutments adapted to operate the dog for clamping plates of respectively different columnar widths, and means adapted to move the rod angularly about its axis to bring the ribs into and out of alinement with the grooves.

4. In a device for clamping printing plates to a cylinder of a printing press, the combination with a plurality of rods movable relatively to the cylinder parallel with the axis thereof, and a corresponding plurality of dogs adapted to be moved by such movement of the rods into and out of engagement with the printing plates and to be moved independently of the rods into and out of engagement with abutments on the rods, of grooves in each dog, an abutment on each rod adapted to operate the respective dog for clamping plates of one columnar width, ribs on each rod constituting an abutment adapted to operate the respective dog for clamping plates of another columnar width, and means adapted to simultaneously move all the rods angularly about their respective axes to bring the ribs into and out of alinement with the grooves.

5. In a device for clamping printing plates to a cylinder of a printing press, the combination with a plurality of rods movable relatively to the cylinder parallel with the axis thereof, and a corresponding plurality of dogs adapted to be moved by such movement of the rods into and out of engagement with the printing plates and to be moved independently of the rods into and

out of engagement with abutments on the rods, of grooves in each dog, a plurality of sets of ribs on each rod constituting abutments adapted to operate the respective dog for clamping plates of respectively different columnar widths, and means adapted to simultaneously move all the rods angularly about their respective axes to bring the ribs into and out of alinement with the grooves.

6. In a device for clamping printing plates to a cylinder of a printing press, the combination with a plurality of rods movable relatively to the cylinder parallel with the axis thereof, and a corresponding plurality of dogs adapted to be moved by such movement of the rods into and out of engagement with the printing plates and to be moved independently of the rods into and out of engagement with abutments on the rods, of grooves in each dog, an abutment on each rod adapted to operate the respective dog for clamping plates of one columnar width, ribs on each rod constituting an abutment adapted to operate the respective dog for clamping plates of another columnar width, means adapted to simultaneously move all the rods angularly about their respective axes to bring the ribs into and out of alinement with the grooves, and means adapted to simultaneously move all the rods in a direction parallel with the axis of the cylinder.

7. In a device for clamping printing plates to a cylinder of a printing press, the combination with a plurality of rods movable relatively to the cylinder parallel with the axis thereof, and a corresponding plurality of dogs adapted to be moved by such movement of the rods into and out of engagement with the printing plates and to be moved independently of the rods into and out of engagement with abutments on the rods, of grooves in each dog, a plurality of sets of ribs on each rod constituting abutments adapted to operate the respective dog for clamping plates of respectively different columnar widths, means adapted to simultaneously move all the rods angularly about their respective axes to bring the ribs into and out of alinement with the grooves, and means adapted to simultaneously move all the rods in a direction parallel with the axis of the cylinder.

8. In a device for clamping printing plates to a cylinder of a printing press, the combination with a rod movable relatively to the cylinder parallel with the axis thereof, and a dog adapted to be moved by that movement of the rod into and out of engagement with the printing plates and to be moved independently of the rod into and out of engagement with abutments on the rod, of grooves in the dog, an abutment on the rod adapted to operate the dog for

- clamping plates of one columnar width, a plurality of sets of ribs on the rod constituting abutments adapted to operate the dog for clamping plates of respectively different columnar widths, and means adapted to move the rod angularly about its axis to bring the ribs into and out of alinement with the grooves.
9. In a device for clamping printing plates to a cylinder of a printing press, the combination with a plurality of rods movable relatively to the cylinder parallel with the axis thereof, and a corresponding plurality of dogs adapted to be moved by such movement of the rods into and out of engagement with the printing plates and to be moved independently of the rods into and out of engagement with abutments on the rods, of grooves in each dog, an abutment on each rod adapted to operate the respective dog for clamping plates of one columnar width, a plurality of sets of ribs on each rod constituting abutments adapted to operate the respective dog for clamping plates of respectively different columnar widths, and means adapted to simultaneously move all the rods angularly about their respective axes to bring the ribs into and out of alinement with the grooves, and means adapted to simultaneously move all the rods in a direction parallel with the axis of the cylinder.
10. In a device for clamping printing

plates to a cylinder of a printing press, the combination with a plurality of rods movable relatively to the cylinder parallel with the axis thereof, and a corresponding plurality of dogs adapted to be moved by such movement of the rods into and out of engagement with the printing plates and to be moved independently of the rods into and out of engagement with abutments on the rods, of grooves in each dog, an abutment on each rod adapted to operate the respective dog for clamping plates of one columnar width, a plurality of sets of ribs on each rod constituting abutments adapted to operate the respective dog for clamping plates of respectively different columnar widths, means adapted to simultaneously move all the rods angularly about their respective axes to bring the ribs into and out of alinement with the grooves, and means adapted to simultaneously move all the rods in a direction parallel with the axis of the cylinder.

In witness whereof we have hereunto set our hands in the presence of two witnesses.
